UNITED STATES PATENT OFFICE.

JOHN DOTY, OF BUFFALO, NEW YORK.

IMPROVEMENT IN FEEDING MECHANISMS FOR ROCK-DRILLS.

Specification forming part of Letters Patent No. **140,767**, dated July 15, 1873; application filed May 3, 1873.

To all whom it may concern:

Be it known that I, JOHN DOTY, of Buffalo, in the county of Erie and State of New York, have invented certain new and useful Improvements in Rock-Drills, of which the following is a specification:

This invention relates to an improvement in the manner of working the feed-lever which operates the bit of the drill, and the feed-catch or "qualifier" employed in what are known as the Burleigh rock-drill. The invention consists in the combination, with the feed-box, of a coiled spring and a qualifier having a pin, to which said spring is attached, the other end working or bearing in a slot in the feed-box. It further consists in a novel and peculiar-formed qualifier, which is fully hereinafter explained; and it further consists of certain other improvements, all of which are herein fully described.

In the drawings, Figure 1 is an elevation with one side of the feed-box removed. Fig. 2 is a plan. Fig. 3 is a perspective view of the qualifier.

A represents the feed-box, the top having grooves *a* for the cover *a'* to slide in. B is the feed-lever, which, in connection with the other parts, turns the bit; and C is the feed-catch or qualifier. In place of the flat steel spring now used to throw the feed-lever back after it has been thrown up by the projection D, I arrange a coiled spring, *b*, as shown, one end resting on the back of the lever and the other against the feed-box cover. To hold it in place I make a kind of box by setting at right angles with and in the sides of the feed-box A two partitions, *c c'*. This prevents the spring from falling out of position, but can be taken out by removing cover *a'* of the feed-box. The lower ends of the partitions *c c'* do not come down to the lever-arm, but allow of a free movement of it, one partition, *c'*, being shorter than the other for that purpose. As fast as the lever is thrown up by the piston-head it is returned to its normal position by the spring.

This spring might be held by a pin attached to the lever, and another inserted through the cover of the feed-box and through the center of the spring; but the way shown is preferable, being simpler.

I am aware that usually the change of one kind of spring for another is not considered invention; but in this case the change and arrangement of springs is of so much importance in working and value to the machine that it is now considered well-nigh indispensable.

The same kind of spiral spring, *e*, is used also in the feed-box in connection with the qualifier C, the latter working on a pivot, *d*. The spring *e* is held in place by its lower end inclosing a pin, *f*, attached to the lower or pointed end of the qualifier, the other end of the spring resting in a slot, *g*, made in the end of the feed-box, the cover *a'* aiding to hold the spring in place, and also allowing its being easily taken out.

The improved form of the qualifier or feed-catch C is of very great importance also; and the objections to the others I overcome by making a more gradual rounding of the lower part, and the relative position of the end with the other parts making a new feed-catch of it.

I claim—

1. The combination of the coiled spring *e*, qualifier C, pin *f*, and slot *g*, arranged and operating substantially as described.
2. The qualifier C with its pin *f*, constructed substantially as described, for the purpose specified.
3. The lever B and qualifier C, in combination with the coiled springs *b e* and projection D, arranged and operating substantially as herein described.

In witness whereof I have hereunto signed my name in the presence of two subscribing witnesses.

J. DOTY.
